UNITED STATES PATENT OFFICE.

JACOB GEIGER, OF STUTTGART, WÜRTEMBERG, GERMANY.

CARD-BOARD-BOX FASTENING.

SPECIFICATION forming part of Letters Patent No. 367,970, dated August 9, 1887.

Application filed December 30, 1886. Serial No. 222,986. (No model.)

To all whom it may concern:

Be it known that I, JACOB GEIGER, manufacturer of card-board boxes in Stuttgart, Würtemberg, Germany, have invented certain new and useful Improvements in Machines for Making Metal Fastening Clips for Card-Board and like Boxes, of which the following is a specification.

This invention relates to certain new and useful improvements in machines for shaping angle-clips for pasteboard and veneer boxes, and also relates to a machine for securing the angle-clips to the box.

The invention consists, first, in the combination, with sliding male and female dies for bending the clips at right angles, of levers operated at the same time with the dies for the purpose of bending over the prongs of the clips.

20 The invention further consists in the combination, with a V-shaped trough for receiving the corner of the box, of pressing-plates for bending over the ends of the prongs of the clips.

25 The invention also consists in the construction and combination of parts and details, as will be fully described and set forth hereinafter, and finally pointed out in the claims.

In the accompanying drawings, Figure 1 is 30 a side view of my improved machine for shaping sheet-metal angle-clips, parts being in section. Fig. 2 is a plan view of the same. Fig. 3 is a face view of one of the blanks for making the clips. Fig. 4 is a sectional plan view of 35 the same. Fig. 5 is a sectional plan view of the clip bent. Fig. 6 is a sectional plan view of the clip having the prongs bent.

Similar letters of reference indicate corresponding parts.

40 The female die *m*, which is provided with a V-shaped groove, into which part of the blank *o* is pressed, is mounted to slide transversely in a slot in the frame or body *A* of the machine, said female die *m* being connected pivotally at *t* with one end of a lever, *h*, pivoted at *i*. A cam, *w*, on a shaft, *W*, acts on that end of the lever *h* opposite the one connected with the female die *m*.

The male die *p*, which fits into the groove

of the female die *m*, is secured on a slide, *f*, 50 which is operated by a cam, *d*, on the shaft *W*. Two levers, *e*, are pivoted at *e* in the frame *A*, each lever having one end adjacent to the side of the male die *p* and the other end resting against the cam projections *x*, of which 55 there is one on each side of the cam *d*. A spring, *K*, is fastened to the lever *h* and to the fixed part of the frame, and draws the female die *m* into the position shown in full lines in Fig. 1.

On that part of the frame in which the female die *m* slides projections are provided at the sides of said sliding female die, which projections serve for registering the blank *o*. When the female die is in the position shown 65 in full lines, the blank *o*, having the side prongs, *z*, is placed over the V-shaped groove in the female die, and, with the said die *m*, enters the slot in the frame *A*, and then the cam *d*, acting on the slide *f*, presses the male die *p* 70 against the clip, whereby the same is pressed into the shape shown in Fig. 5—that is, V-shaped. The projections *x* then act on the levers *e*, whereby the front ends of the levers *e* press the prongs *z* of the blank *o* into the position shown in Fig. 6. The lever *h* is then moved into the position shown in full lines in Fig. 1 and the clip drops out of the machine. The spring *f* serves to draw the levers *e* toward each other.

Having thus described my invention, I claim as new and desire to secure by Letters Patent—

1. The combination, with a frame, *A*, of a sliding die, *p*, and a die, *m*, mounted to slide in a slot in the frame at the lower end of a 85 sliding die, *p*, which slot is at right angles to the direction in which the die *p* slides, so that the said die *m* will slide at right angles to the die *p*, substantially as shown and described.

2. The combination, with the frame *A*, of 90 the female die *m*, having a V-shaped groove and mounted to slide transversely in the frame, the die *p*, mounted to slide longitudinally in the frame, and the levers *e*, having their ends adjacent to the die *p*, substantially as shown 95 and described.

3. The combination, with the frame *A*, of the die *m*, mounted to slide transversely in the

same, the pivoted lever *h*, connected with the die *m*, the shaft *W*, the cam *w* on the same, the slide *f*, the cam *d*, acting on the same, the die *p* on the slide *f*, and the two pivoted levers *e*, having their ends adjacent to the die *p* and cam *d*, substantially as shown and described.

In testimony that I claim the foregoing as my invention I have signed my name in presence of two subscribing witnesses.

JACOB GEIGER.
